UNITED STATES PATENT OFFICE

2,502,303

ELECTRICAL CONNECTOR

Samuel L. Arson, Glendale, and Robert J. Cannon, Los Angeles, Calif., assignors to Cannon Electric Development Company, Los Angeles, Calif., a corporation of California

Application March 8, 1948, Serial No. 13,693

5 Claims. (Cl. 173—328)

1

Our invention relates in general to electrical connectors and, more particularly, to a connector which comprises a pair of telescopically connectible and disconnectible terminal members, such as a plug and a socket, a primary object of the invention being to provide an improved latching means for releasably securing the two terminal members together after they have been telescopically connected.

An important object of the invention is to provide an electrical connector wherein one of the terminal members is provided with a generally keyhole-shaped opening which includes an aperture and a slot communicating with the aperture, and wherein the other terminal member is provided with a latch having a portion which is insertable through the slot into the aperture during relative telescoping movement of the terminal members, and having a second, enlarged portion which is subsequently insertable into the aperture to secure the terminal members together.

More specifically, an object of the invention is to provide a connector of the foregoing character wherein the latch is movable between extended and retracted positions, the aforementioned first portion of the latch being insertable into and movable through the slot into alignment with the aperture during relative telescoping movement of the terminal members toward each other with the latch in its retracted position, and the second portion of the latch being insertable into the aperture when the latch is moved from its retracted position to its extended position with the first portion thereof in alignment with the aperture.

Another object is to provide an electrical connector having resilient means for biasing the latch toward its extended position and having manually operable means for moving the latch from its extended position to its retracted position.

Still another object is to provide an electrical connector having cam means for moving the latch from its extended position to its retracted position automatically during relative telescoping movement of the terminal members toward each other. A related object is to provide a connector wherein the cam means comprises a cam surface defined by a shoulder on the latch at the junction of the first and second portions thereof, the shoulder being inclined with respect to the direction of movement of the latch between its extended and retracted positions.

Another object of the invention is to provide an electrical connector wherein each terminal in-

2

cludes a shell having a core therein and includes a spring-pressed detent carried by the core for securing the core in the shell. This construction eliminates the use of screws or the like for holding the components of each terminal in assembled relationship, and thus facilitates assembly and disassembly thereof, which is an important feature of our invention.

A further object is to provide an electrical connector comprising telescopically connectible and disconnectible terminal members wherein each terminal member is provided with a generally semi-cylindrical surface and a generally plane surface and wherein the semi-cylindrical surface and the plane surface of one terminal member are aligned with the semi-cylindrical surface and the plane surface, respectively, of the other terminal member when the members are connected. This construction facilitates orienting the terminal members with respect to each other so that they may be connected readily and also tends to prevent the connector from rolling when it is placed on a flat surface, which are important features of the invention.

The foregoing objects of our invention and the advantages suggested thereby, together with various other objects and advantages which will be evident, may be attained through the utilization of the exemplary embodiments of the invention which are illustrated in the accompanying drawings and which are described in detail hereinafter. Referring to the drawings:

Fig. 1 is a plan view of an electrical connector which embodies the invention;

Fig. 2 is an enlarged, longitudinal sectional view which is taken along the broken line 2—2 of Fig. 1;

Figs. 3, 4 and 5 are transverse sectional views which are taken along the broken lines 3—3, 4—4 and 5—5, respectively, of Fig. 2;

Fig. 6 is an enlarged, fragmentary sectional view which is taken along the broken line 6—6 of Fig. 2;

Fig. 7 is a plan view of another embodiment of the invention;

Fig. 8 is an enlarged, longitudinal sectional view which is taken along the broken line 8—8 of Fig. 7;

Fig. 9 is an end view of a terminal member of the connector illustrated in Fig. 7;

Fig. 10 is a plan view of still another embodiment of the invention;

Fig. 11 is an enlarged, longitudinal, sectional view which is taken along the broken line 11—11 of Fig. 10;

Fig. 12 is an end view of a terminal member forming part of the connector illustrated in Fig. 10; and

Fig. 13 is an enlarged, fragmentary sectional view which is taken along the broken line 13-13 of Fig. 11.

Referring particularly to Fig. 1 of the drawings, we show an embodiment of the invention, indicated generally by the numeral 15 and referred to hereinafter as a cable connector, which may be used for connecting two cables 16 and 17, each cable including three wires in the particular construction illustrated. The wires of the cable 16 are identified by the numerals 18 and those of the cable 17 are identified by the numerals 19. The cables 16 and 17 may, for example, represent parts of a portable microphone circuit and the cable connector 15 is of particular utility when used in such a circuit, although it will be understood that many other uses therefor come within the scope of the invention.

As best shown in Figs. 1 and 2 of the drawings, the cable connector 15 includes two terminal members 21 and 22, the member 21 being a plug and the member 22 being a socket in the particular construction illustrated. Considering the plug 21 in more detail, it comprises a tubular shell 23 having therein a core 24, the latter being insertable into the shell from one end thereof. The core 24 is formed of a suitable insulating material and the shell 23 is preferably, although not necessarily, formed of metal. In the particular construction illustrated, the core 24 carries three plug contacts 25 each of which includes an enlarged portion 26 pressed into an opening 27 in the core. Each plug contact 25 also includes a prong or pin 28 and a terminal end 29, the pin extending through an insulator 30 which is disposed in the shell 23 adjacent the core 24.

The wires 18 forming the cable 16 are connected to the terminal ends 29 of the plug contacts 25, respectively, in any suitable manner, as by soldering, for example, the cable 16 being secured by a clamp 33. The latter includes a gland 34 having a cylindrical portion 35 which is pressed into one end of the shell 23, and includes a clamping strap 36 which may be secured to the gland by screws 37, or the like, to secure the cable 16 with respect to the shell 23.

Considering the socket 22, it includes a shell 41 having therein a core, indicated generally by the numeral 42, which may be inserted into the shell from one end thereof. The core 42 comprises a barrel or sleeve 43 which is preferably, although not necessarily, formed of metal and which receives an insulator 44, the latter being provided with three openings 45, in the particular construction illustrated, into which three socket contacts 46 are respectively pressed. The core 42 is adapted to be telescoped into the shell 23 of the plug 21 so that the pins 28 of the plug contacts 25 engage the respective socket contacts 46, each of the socket contacts being provided with a sleeve 47 which is adapted to receive one of the pins. The socket contacts extend through an insulator 48 and terminate in ends 49 to which the respective wires 19 of the cable 17 may be soldered or otherwise secured. The socket 22 includes a clamp 50 for securing the cable 17 with respect to the shell 41 thereof. The clamp 50 is substantially identical to the clamp 33 of the plug 21 so that it is not necessary to describe it in detail.

As will be apparent, the wires 18 of the cable 16 may be connected to the respective wires 19 of the cable 17 by telescopically connecting the plug 21 and the socket 22 so that the pins 28 of the plug contacts 25 enter the sleeves 47 of the respective socket contacts 46. Conversely, the cables 16 and 17 may be disconnected readily by separating the plug 21 and the socket 22.

As indicated previously, an important feature of the present invention resides in the provision of a latching means, indicated generally by the numeral 54, which prevents inadvertent separation of the plug 21 and socket 22 and which is readily releasable so that the plug and socket may be connected and disconnected easily whenever desired. As best shown in Fig. 2 of the drawings, the latching means 54 comprises a latch 55 which is disposed partially within a slot 56 in the shell 41 of the socket 22, the latch being provided with an end portion 57 which engages one end of the barrel 43 of the core 42 and which engages the peripheral wall of the shell 41 to secure the latch. This connection between the latch 55 and the shell 41 and barrel 43 permits limited pivotal movement of the latch in a vertical plane, as viewed in Fig. 2 of the drawings, about the end portion 57 thereof. The latch 55 is provided with a serrated surface 58 so that it may be depressed, i. e., moved downwardly as viewed in Fig. 2, readily by a thumb or fingertip of an operator as will be discussed in more detail hereinafter.

The latch 55 includes another end portion 59 which comprises a first portion 61 of reduced size and a second or enlarged portion 62 substantially aligned with the first portion 61, the first and second portions cooperating to define a pair of inclined shoulders or cam surfaces 63, as best shown in Figs. 2 and 3 of the drawings. The shell 23 of the plug 21 is provided with a generally keyhole-shaped opening which, as best shown in Fig. 6 of the drawings, comprises an aperture 65 spaced inwardly from one end 67 of this shell and a slot 66 communicating with the aperture. The slot 66 is adapted to receive the first portion 61 of the latch 55 and the aperture 65 is adapted to receive the enlarged portion 62 thereof, the diameter of the enlarged portion 62 being greater than the width of the slot 66 so that it cannot be withdrawn through the slot. The latch 55 is normally biased toward an extended position, viz., the position illustrated in Fig. 2 of the drawings, by a leaf spring 69 so as to retain the enlarged portion 62 of the latch in the aperture 65, the spring being disposed in a recess 70 in the insulator 44 forming part of the core 42. It will be noted that the enlarged portion 62 of the latch 55 extends through an opening 71 in the barrel 43 into engagement with the spring 69.

Considering the operation of the latching means 54, it will be apparent that since the diameter of the enlarged portion 62 of the latch 55 is greater than the width of the slot 66 in the shell 41 of the socket 22, the enlarged portion of the latch serves to secure the plug 21 and the socket 22 together as long as the latch is in its extended position, the latch normally being retained in its extended position by the spring 69. Whenever separation of the plug 21 and socket 22 is desired, it is merely necessary to depress or retract the latch, i. e., move the latch downwardly from the position shown in Fig. 2 of the drawings, so as to withdraw the enlarged por-

tion 62 thereof from the aperture 65. This may be accomplished readily by pressing inwardly on the serrated surface 58 of the latch 55. Subsequently, the plug 21 and socket 22 may be separated readily, the portion 61 of the latch 55 moving through the slot 66 in the shell 41 of the socket as the plug and socket are separated. Thus, it will be apparent that in order to disconnect the plug 21 and socket 22, it is merely necessary to depress the latch 55 and pull the plug and socket apart, which is an important feature of the invention.

In order to connect the plug 21 and socket 22, it is merely necessary to insert the core 42 of the socket into the shell 23 of the plug with the portion 61 of the latch 55 in alignment with the slot 66 in the shell 23. The cam surfaces 63 between the first and second portions 61 and 62 of the latch 55 engage the end 67 of the shell 23 so as to move the latch 55 from its extended position into its retracted position as the plug 21 and socket 22 are telescoped together, thereby moving the portion 61 of the latch into alignment with the slot 66 so that it may enter and move through the slot into the aperture 65. Subsequently, the spring 69 urges the latch 55 into its extended position so as to insert the enlarged portion 62 of the latch into the aperture 65 to secure the plug 21 and the socket 22 together. Thus, when connecting the plug 21 and the socket 22, it is unnecessary to move the latch 55 to its retracted position manually since this function is performed by engagement of the cam surfaces 63 with the end 67 of the shell 23, which is another important feature of the present invention.

As discussed previously herein, another important feature of our invention resides in the provision of detent means for securing the cores 24 and 42 of the plug 21 and socket 22 within the respective shells 23 and 41 thereof, the detent means associated with the plug 21 being indicated by the numeral 74 and that associated with the socket 22 being indicated by the numeral 75. By eliminating the use of screws or the like for securing the cores 24 and 42 in the shells 23 and 41, the detent means 74 and 75 greatly facilitate assembly and disassembly of the plug 21 and the socket 22, which is an important advantage of the invention.

As best shown in Figs. 2 and 5, the detent means 74 associated with the plug 21 comprises a button or detent 76 which is carried by the core 24 and which is insertable into an opening 77 in the shell 23 so as to secure the core 24 within this shell. The detent 76 is urged toward an extended position wherein it is inserted into the opening 77 by a spring 78, the latter being disposed in a receptacle 79 which is disposed in a recess 80 in the core 24. The receptacle 79 is provided with an inturned lip 81 which is engageable with an annular flange 82 on the detent 76 to limit movement of the detent under the action of the spring 78. It will be apparent that in order to assemble the core 24 in the shell 23, it is merely necessary to depress the detent 76 with respect to the core and subsequently insert the core into the shell in such a manner that the detent is aligned with the opening 77 in the shell, whereupon the spring 78 moves the detent to its extended position to retain the core within the shell. If necessary, the core 24 may be removed from the shell 23 by reversing the foregoing sequence of operations.

The detent means associated with the socket

22 includes a detent 85 which is carried by the core 42 and which extends through an opening 86 in the barrel 43 of the core 42, the detent 85 being insertable into an opening 87 in the shell 41 of the socket 22 to secure the core 42 within this shell. The detent 85 is biased toward an extended position wherein it is disposed in the opening 87 in the shell 41 by the spring 69 for extending the latch 55 so that the spring 69 serves as a single resilient means for biasing both the latch 55 and the detent 85 toward their extended positions, which is an important feature of the invention. It will be noted that the enlarged portion 62 of the latch 55 and the detent 85 are interconnected by a strap 88, the function of this strap being to prevent detachment of the latch from the socket 22. The operation of the detent means 75 is similar to that of the detent means 74 and will not be discussed in detail.

As best shown in Figs. 3, 4 and 5 of the drawings, the shell 23 of the plug 21 is provided with a generally semi-cylindrical surface 91 and a substantially plane surface 92, the keyhole-shaped opening 64 being formed in the plane surface 92 of this shell. Similarly, the shell 41 of the socket 22 is provided with surfaces 93 and 94 which correspond to and are adapted to be aligned with the surfaces 91 and 92 of the shell 23 when the plug 21 and socket 22 are to be connected, the latch 55 being disposed adjacent the plane surface 94 of the shell 41. The cores 24 and 42 of the plug 21 and socket 22 correspond in shape to the shells 23 and 41, respectively.

The plane surfaces 92 and 94 of the shells 23 and 41 provide the assembled connector 15 with a flat side which prevents the connector from rolling when it is placed on a flat surface, such as a table top, which is common when the connector 15 is used with portable microphones, for example. As indicated in Fig. 1 of the drawings, the clamps 33 and 50 on the plug 21 and socket 22 may be enclosed by sleeves 95 and 96, respectively, of rubber, neoprene, or the like, for the purpose of protecting surfaces on which the cable connector 15 may be placed, the sleeves 95 and 96 being provided with flat sides, identified by the numerals 97 and 98, which register with the plane surfaces 92 and 94 of the plug and socket and which assist in preventing rolling of the connector over a surface on which it may be placed.

Referring now to Figs. 7 to 9 of the drawings, the embodiment of our invention which is illustrated therein comprises a socket 102 which is adapted to receive a plug such as the plug 21 and which is adapted to be mounted on a control panel, wall, or the like. The socket 102 is similar to the socket 22 and includes a receptacle or shell 103, a core 104 within this shell, and latching means 105 for releasably connecting the plug 21 and the socket 102. The core 104 is substantially identical to the core 42 of the socket 22 and need not be described in detail.

Referring particularly to Figs. 8 and 9 of the drawings, the shell 103 is adapted to receive the shell 23 of the plug 21 therein and is provided with a flange 106 having openings 107 therein for the reception of screws or the like (not shown) for attaching the socket 102 to a control panel, wall, etc., the flange 106 being rectangular in the particular construction illustrated although it will be understood that any suitable configuration may be employed. The latching means 105 comprises a latch 111 having a first portion 112 of reduced size and a second, enlarged portion 113 which correspond to the portions 61 and 62,

respectively, of the latch 55. The portions 112 and 113 of the latch 111 are joined by inclined cam surfaces 114 which correspond to the cam surfaces 63 of the latch 55. The portion 112 of the latch 111 is receivable by the slot 66 in the shell 23 of the plug 21 and the enlarged portion 113 thereof is receivable by the aperture 65 in the shell 23, the latch 111 being biased toward an extended position wherein it is inserted into the aperture 65 by a leaf spring 115 which corresponds to the spring 69 of the socket 22. The latch 111 may be depressed into a retracted position, by a lever 116 which is disposed in a recess 117 in the shell 103. One end of the lever 116 is doubled back, as indicated by the numeral 118, and is adapted to engage the latch 111 to retain the lever within the recess 117. It will be noted that the lever 116 is, in effect, mounted for pivotal movement about the end 119 of the doubled back portion thereof.

It will be apparent that in order to disconnect the plug 21 and the socket 102, it is merely necessary to depress the lever 116 downwardly to move the portion 112 of the latch 111 into alignment with the slot 66 in the shell 23 of the plug whereupon the plug and socket may be separated, the portion 112 of the latch moving through the slot 66 as the plug is withdrawn from the socket. In order to connect the plug 21 and socket 102, it is merely necessary to insert the plug into the socket with the slot 66 in the shell 23 of the plug in alignment with the latch 111. The cam surfaces 114 on the latch 111 engage the end 67 of the shell 23 and move the latch into its retracted position so that the portion 112 thereof enters and moves through the slot 66 into the aperture 65. Subsequently, the spring 115 extends the latch 111 so that the enlarged portion 113 thereof enters the aperture 65 to secure the plug 21 and socket 102 together.

The socket 102 also includes a detent means 122 for securing the core 104 thereof within the shell 103, this detent means comprising a button or detent 123 which is insertable into an opening 124 in the shell and which is movable into an extended position wherein it is disposed in the opening 124 by the spring 115. Thus, as is the case with the socket 22, the latch 111 and the detent 122 are both actuated by the same spring. It will be noted that the latch 111 and the detent 122 are interconnected by a strap 125 which serves to limit movement thereof under the action of the spring 115.

Referring to Figs. 10 to 13 of the drawings, the embodiment of our invention illustrated therein comprises a plug 131 which is similar to the plug 21 and which is connectable to the socket 22, the plug 131 being adapted to be mounted on a control panel, wall, or the like. As best shown in Fig. 11 of the drawings, the plug 131 includes a shell 132 having a core 133 therein and includes detent means 134 for retaining the core within the shell. The core 133 and the detent means 134 of the plug 131 are substantially identical to the corresponding components of the plug 21 and need not be described in detail herein.

The shell 132 of the plug 131 is provided with a flange 135 having holes 136 therein for the reception of screws or the like for mounting the plug 131 on a control panel, wall, etc., the flange 135 being rectangular in the particular construction illustrated although it will be understood that other configurations may be employed.

As best shown in Figs. 11 and 13 of the drawings, the shell 132 of the plug 131 is provided with a keyhole-shaped opening 137 which corresponds to and performs the same function as the keyhole-shaped opening 64 in the shell 23 of the plug 21, the opening 137 comprising an aperture 138 which is spaced inwardly from an end 139 of the shell 132 and comprising a slot 140 which communicates with the aperture 138. The flange 135 of the shell 132 is provided with an opening 141 which is adapted to receive the latch 55 of the socket 22.

The operation of the plug 131 in connection with the socket 22 is similar to the operation of the plug 21 in connection therewith and need not be described in detail. Briefly, in order to connect the plug 131 and the socket 22, it is merely necessary to insert the core 42 of the socket 22 into the shell 132 of the plug 131 with the latch 55 in alignment with the slot 140, whereupon the cam surfaces 63 on the latch 55 engage the end 139 of the shell 132 so as to retract the latch and move the portion 61 thereof into alignment with the slot 140. Subsequently, the portion 61 of the latch 55 enters and moves through the slot 140 into the aperture 138 so that the spring 69 may extend the latch and insert the enlarged portion 62 thereof into the aperture. The plug 131 and socket 22 may be disconnected by depressing the latch 55 and subsequently withdrawing the core 42 of the socket 22 from the shell 132 of the plug 131.

It will thus be apparent that our invention provides an electrical connector having terminals which may be connected and disconnected readily and which cannot be inadvertently disconnected, and provides an improved means for holding the components of the terminals in assembled relationship. Although we have disclosed exemplary embodiments of our invention herein for purposes of illustration, it will be understood that we do not intend to be limited specifically thereto since various changes, modifications and substitutions may be incorporated in the embodiments disclosed without necessarily departing from the spirit of the invention, and we hereby reserve the right to all such changes, modifications and substitutions as properly come within the scope of the invention as set forth in the appended claims.

We claim as our invention:

1. In an electrical connector, the combination of: relatively telescopic terminal members one of which is provided with an aperture spaced inwardly from an end thereof, said one member being provided with a slot extending inwardly from said end thereof and communicating with said aperture, the width of said slot being less than that of said aperture; a latch carried by the other of said members and movable relative thereto between extended and retracted positions, said latch being provided with a first portion which is insertable into and movable through said slot into alignment with said aperture during relative telescoping movement of said members toward each other with said latch in said retracted position, and being provided with a second, enlarged portion which is insertable into said aperture when said latch is moved from said retracted position to said extended position with said first portion thereof in alignment with said aperture, said first and second portions of said latch being aligned in the direction of its movement between said extended and retracted positions; and cam means on said latch engageable

with said one member for moving said latch from said extended position to said retracted position during relative telescoping movement of said members toward each other, said cam means comprising a shoulder on said latch at the junction of said first and second portions thereof, said shoulder being inclined at an acute angle to the direction of relative telescoping movement of said members.

2. In an electrical connector, the combination of: relatively telescopic plug and socket members one of which is provided with a shell and the other of which is insertable into said shell during relative movement of said members toward each other, said shell being provided with an aperture spaced inwardly from an end thereof and being provided with a slot extending inwardly from said end thereof and communicating with said aperture, the width of said slot being less than that of said aperture; a latch carried by said other member and movable relative thereto between extended and retracted position, said latch being provided with a first portion which is insertable into and movable through said slot into alignment with said aperture during relative telescoping movement of said members toward each other with said latch in said retracted position, and being provided with a second, enlarged portion which is insertable into said aperture when said latch is moved from said retracted position to said extended position with said first portion of said latch in alignment with said aperture, said first and second portions of said latch being aligned in the direction of its movement between said extended and retracted positions; and cam means on said latch engageable with said one member for moving said latch from said extended position to said retracted position during relative telescoping movement of said members toward each other, said cam means comprising a pair of shoulders on said latch at the junction of said first and second portions thereof, said shoulders being inclined at an acute angle to the direction of relative telescoping movement of said members.

3. An electrical connector including relatively telescopic plug and socket members one of which is provided with a generally keyhole-shaped opening comprising an aperture and a slot communicating with said aperture; a latch carried by the other of said members and movable relative thereto between retracted and extended positions, said latch being provided with a first portion which is insertable into said slot and being provided with a second, enlarged portion which is insertable into said aperture and which is substantially aligned with said first portion of said latch, said first portion being movable through said slot into said aperture during relative telescoping movement of said members toward each other so as to align said second portion with said aperture, said latch subsequently being movable from its retracted position to its extended position so as to insert said second portion into said aperture, said first and second portions of said latch being aligned in the direction of its movement between said extended and retracted positions; cam means on said latch engageable with said one member for moving said latch from said extended position to said retracted position during relative telescoping movement of said members toward each other, said cam means comprising a pair of shoulders on said latch at the junction of said first and second portions thereof, said shoulders being inclined at an acute angle

to the direction of relative telescoping movement of said members; and resilient means for biasing said latch toward its extended position.

4. In an electrical connector, the combination of: relatively telescopic plug and socket members one of which includes a shell and the other of which includes a shell having a core therein which is insertable into said shell of said one member during relative telescoping movement of said members toward each other, said shell of said one member being provided with an aperture spaced inwardly from an end thereof and being provided with a slot extending inwardly from said end thereof and communicating with said aperture, the width of said slot being less than that of said aperture, and said shell of said other member being provided with an opening; a latch carried by said core and movable relative thereto between extended and retracted positions, said latch being provided with a first portion which is insertable into and movable through said slot into alignment with said aperture during relative telescoping movement of said members toward each other with said latch in said retracted position, and being provided with a second, enlarged portion which is insertable into said aperture when said latch is moved from said retracted position to said extended position with said first portion of said latch in alignment with said aperture; a detent carried by said core and movable from a retracted position to an extended position wherein it is inserted into said opening in said shell of said other member to retain said core therein; and a single resilient means for urging said latch and said detent toward their respective extended positions.

5. In an electrical connector, the combination of: relatively telescopic terminal members one of which includes a shell having a core therein, said shell of said one member being provided with an opening and the other of said members being provided with an aperture; a latch carried by said one member and movable relative thereto between extended and retracted positions, said latch being insertable into said aperture upon movement thereof from said retracted position to said extended position with said members telescoped together; a detent carried by said core and movable from a retracted position to an extended position wherein it is inserted into said opening in said shell of said one member to retain said core therein; and a single spring carried by said one member and engaging both said latch and said detent for biasing said latch and said detent toward their respective extended positions.

SAMUEL L. ARSON.
